(57) **CLAIM**

The ornamental design for a an electronic keyboard with microphone, as shown and described.

DESCRIPTION

FIG. 1 is a top perspective view of an electronic keyboard with microphone showing my new design;

FIG. 2 is a bottom perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front view thereof;

FIG. 8 is a rear view thereof;

FIG. 9 is a perspective view thereof, illustrating the design in another configuration with the microphone and base of the design folded down; and,

FIG. 10 is an enlarged view of the section taken at line-10 in FIG. 1.

The broken lines shown in the drawings depict portions of the an electronic keyboard with microphone in which the design is embodied that form no part of the claimed design.
